UNITED STATES PATENT OFFICE.

JOHN L. FRYSINGER, DECEASED, LATE OF OKLAHOMA, OKLAHOMA, BY PERRY P. FRYSINGER AND ULVA O. FRYSINGER, ADMINISTRATORS, OF INGERSOLL AND BEAVER, OKLAHOMA, ASSIGNS, BY DIRECT AND MESNE ASSIGNMENTS, TO THE HERMETIC GLASS CASKET COMPANY, OF OKLAHOMA COUNTY, OKLAHOMA.

BURIAL-CASKET.

1,244,315.

Specification of Letters Patent. Patented Oct. 23, 1917.

Application filed March 31, 1917. Serial No. 158,887.

To all whom it may concern:

Be it known that JOHN L. FRYSINGER, deceased, a former citizen of the United States, formerly residing at Oklahoma city, in the county of Oklahoma and State of Oklahoma, has invented certain new and useful Improvements in Burial-Caskets, of which the following is a specification, reference being had to the accompanying drawings.

10 This invention relates to burial caskets or coffins and the general object of the invention is to provide a novel form of casket which is preferably constructed of glass or other transparent or translucent material, 15 the body of the casket being reinforced by thickened ribs extending around the casket, the casket being so formed that the body, placed upon a suitable slide, plate, or pan, may be inserted within the casket and then 20 the end of the casket sealed.

A further object of the invention is to provide a casket of this character very strongly reinforced by surrounding bands and provide means for supporting the handle rods of the casket on these bands, and permitting said rods to be lifted to an operative position for carrying the casket or lowered to an inoperative position.

A further object of the invention is to 30 provide a casket which is practically indestructible and through which the body may be seen if desired.

Other objects will appear in the course of the following description.

35 This invention is illustrated in the accompanying drawings, wherein—

Figure 1 is a top plan view of a burial casket constructed in accordance with this invention;

40 Fig. 2 is a side elevation of the casket partly in section;

Fig. 3 is a fragmentary vertical section through a portion of the casket showing the hinged members for carrying the casket;

45 Fig. 4 is a section on the line 4—4 of Fig. 3.

Fig. 5 is a section on the line 5—5 of Fig. 3.

Referring to these drawings, it will be 50 seen that the casket 10 is preferably composed of glass, though it may be formed of other material and this casket has integral side walls and an integral end wall which,

if the casket be made of glass or other like material may be all cast in one piece. The 55 casket is preferably somewhat pyramidal in shape and its larger end is open but is designed to be permanently closed by a closure piece 12 of glass or other material sealed or electrically fused into the opening of the 60 casket. Preferably the top of the casket is formed with a thickened portion 13 extending between two of the ribs 11 and constituting a place for the reception of the name and age of the deceased and, if desired, for 65 the reception of the manufacturer's name. These indicia may be etched into the glass or a metal plate may be attached to this portion 13, the metal plate being properly engraved. 70

Additionally reinforcing the casket are a plurality of metallic bands 14, these bands being preferably disposed in slight recesses 15 formed in the reinforcing ribs 11, the bands tightly surrounding the caskets, and 75 the ends of the bands being brazed, riveted or otherwise strongly connected to each other. To provide means whereby the casket may be lifted and carried and lowered into the grave, I preferably form the bands 80 14 each with a transversely extending bead 16. Pivotally connected to the band 14 is an arm 17, the inner end of this arm being formed with an elongated eye 18 inserted in the bead 16 and the outer end of the arm 85 being formed with an eye 19 through which the lifting rod 20 may pass. Attached to the arm 17 is an elongated loop or bail 21 and formed upon the strip 14 is an outwardly projecting lug 22, T-shaped in form, 90 which extends through the bail, the side bars of the bail being disposed below the T-shaped head. With this construction it is obvious that when the arm 17 is raised, the bail rides upward on the T-shaped lug 95 22 and eventually the lower end of the bail bears against the lug, preventing the further movement of the arm to a position approximately at right angles to the side wall of the casing. Under these circumstances, the 100 rod 20 may be used to lift the casket. If desired, the several arms 17 may be connected permanently to the rod 20 or the rods 20 may be made removable from their supporting arms after the casket has been lowered into the grave. It is obvious that the 105

members 17, 20 and 21 may be formed of an ornamental configuration and add materially to the beauty of the casket.

- Disposed within the casket and supporting the body is a plate or pan designated 23. This has upwardly and outwardly extending margins and is provided at one end with a longitudinally extending member 24. In order to hold the pan in place within the casket, transversely projecting lugs 25 may be provided attached to the walls of the casket or other suitable means may be used for this purpose. It is of course obvious that the lower portion of the casing may be lined and upholstered in the usual manner and it is also obvious that the casket may be used to contain a coffin of the ordinary character, the transparent walls of the casket permitting the coffin to be seen.
- 20 A casket constructed in accordance with this invention will be practically indestructible. The material from which the casket is made may be readily cast and the casket is materially strengthened by the reinforcing ribs extending transversely of it and further strengthened by the bands 14 extending around these ribs. While preferably the

casket is formed of glass, it will be obvious that it might be made of any material which can be molded such as concrete or earthen- 30 ware.

Having described this invention, what is claimed is:

In a casket of the character described, metallic bands surrounding the casket, a 35 plurality of arms pivoted to said metallic bands at the sides of the casket for movement in a vertical plane and having loops at their ends, a bail pivoted to each arm and depending therefrom, and a T-shaped 40 lug for each bail with which the bail has sliding engagement, said lug limiting the upward movement of the bail, and carrying rods inserted through the loops in the ends of the arms. 45

In testimony whereof, we affix our signatures.

PERRY P. FRYSINGER,
ULVA O. FRYSINGER,
Administrators of the estate of John L. Frysinger, deceased.
